United States Patent [19]

Raleigh et al.

[11] Patent Number: Des. 335,088

[45] Date of Patent: ** Apr. 27, 1993

[54] COORDINATE MEASURING MACHINE
WITH COVERS

5,142,790 9/1992 Raho et al. 33/503

[75] Inventors: Freddie L. Raleigh; Frederick K. Bell,
both of Centerville, Ohio

Primary Examiner—Alan P. Douglas

Assistant Examiner—Antoine D. Davis

Attorney, Agent, or Firm—John R. Benefiel

[73] Assignee: Warner & Swasey Co., Sheffield
Measurement Div., Bloomfield Hills,
Mich.

[57] CLAIM

The ornamental design for a coordinate measuring ma-
chine with covers, as shown and described.

[**] Term: 14 Years

DESCRIPTION

[21] Appl. No.: 688,210

FIG. 1 is a perspective view of a coordinate measuring
machine with covers according to the present invention;

[22] Filed: Apr. 22, 1991

FIG. 2 is a front elevational view of the coordinate
measuring machine with covers shown in FIG. 1;

[52] U.S. Cl. D10/46

FIG. 3 is a rear elevational view of the coordinate mea-
suring machine with covers shown in FIG. 1;

[58] Field of Search D10/46, 60, 62, 70;
33/1 M, 1 B, 1 C, 503; 364/371.5

FIG. 4 is a left side elevational view of the coordinate
measuring machine with covers shown in FIG. 1, the

right side elevational view being a mirror image; and,

FIG. 5 is a top view of the coordinate measuring ma-
chine with covers shown in FIG. 1.
